UNITED STATES PATENT OFFICE.

WILLIAM J. BARRETT, OF CHICAGO, ILLINOIS.

WEDGE FOR LOCOMOTIVE DRIVING-BOXES.

No. 873,148.

Specification of Letters Patent.

Patented Dec. 10, 1907.

Application filed February 15, 1907. Serial No. 357,532.

To all whom it may concern:

Be it known that I, WILLIAM J. BARRETT, a citizen of the United States, residing at Chicago, in the county of Cook and State of Illinois, have invented a new and useful Improvement in a Wedge for Locomotive Driving-Boxes, of which the following is a specification.

This invention relates to a device for adjusting wedges employed in connection with drive boxes and binders.

It is customary to support the drive boxes within a frame or jaw, and to lock the same by means of a wedge leaving room for adjustment in order to take up wear from the drive box.

The object of my invention is to improve upon the means heretofore employed for adjusting the wedge when it becomes necessary to tighten the same to take up wear upon the drive box.

My invention consists of the novel features of construction, hereinafter fully described and pointed out in the claims.

In the drawings forming a part of this specification:—Figure 1 is a side elevation of the drive wheel portion of a locomotive illustrating the application of my invention, the drive axles being shown in sections and portions of a driving box being broken away. Fig. 2 is an enlarged side elevation of a portion of a binding frame or jaw, the drive axle being shown in section and a portion of the frame, driving box and wedge, being also shown in section. Fig. 3 is a face view of one of the wedges, a portion of the binder frame being shown in section, and my adjusting means being shown in elevation. Fig. 4 is a perspective view of a wedge.

In these drawings A represents the jaws or binding frame in which is fitted a driving box A' within which is journaled a drive axle A². The pedestals A³ of the frame A are connected by the usual pedestal braces B, bolted in position in the usual manner. The wedge D consists of a metal plate having two side flanges D' which are beveled or tapered ad-

jacent their upper ends as shown at D². Through the pedestal braces D pass two bolts E and E'. The bolt E has its upper end threaded into the lower portion of the wedge D, and is locked by a suitable nut F and a jam nut F'. The bolt E' bears at its upper end upon the lower edge of the wedge D and carries a dead nut G which is provided with a collar G' which collar fits within a suitable recess B' formed in the pedestal brace B. The bolt E' also carries a nut H which bears against the under face of the pedestal brace. It will be obvious that by means of the nuts F and H which are the adjusting nuts, the bolts E and E' may be elevated or lowered. By a construction of this kind the wedge D is held by and operated upon by two bolts, only one of which enters the wedge. A firm support is thereby obtained without at the same time providing a support so rigid that it will be liable to break under strain and continual jar necessarily placed upon it.

Having thus fully described my invention, what I claim as new and desire to secure by Letters Patent, is:—

The combination with a driving box wedge, and a pedestal brace, of an adjusting bolt passing loosely through said brace, the lower end portion of the wedge having a vertically arranged threaded socket receiving the upper end portion of the adjusting bolt, an adjusting nut upon the lower end portion of said bolt, said nut bearing upon the under side of the pedestal brace, a second adjusting bolt passing loosely through the pedestal brace and bearing at its upper end upon the lower end of the wedge, a dead nut arranged upon said bolt, said dead nut having a collar, and the pedestal brace having a socket to receive the collar, and an adjusting nut upon the last mentioned adjusting bolt.

WILLIAM J. BARRETT.
